UNITED STATES PATENT OFFICE.

JOSEPH B. BRADLEY, OF MIAMI, FLORIDA.

SCREEN-HINGE.

1,306,684.

Specification of Letters Patent. Patented June 17, 1919.

Application filed February 11, 1919. Serial No. 276,402.

To all whom it may concern:

Be it known that I, JOSEPH B. BRADLEY, a citizen of the United States, residing at Miami, in the county of Dade and State of Florida, have invented new and useful Improvements in Screen-Hinges, of which the following is a specification.

This invention relates to hinges, and more particularly to sash or screen frame hinges which are mounted in rabbeted places in their frames.

One of the principal objects of the invention is to provide a hinge which is readily attached to the sash or screen frame and which permits of the convenient hanging of the sash or screen without mortising or without materially marring the window frame.

Another object of the invention is the provision of a hinge for vertically swinging window sashes or screens adapted to fit within the rabbet portions of window frames which will absolutely prevent the breaking or splitting of the wood of which the sash or screen is constructed at the point of attachment of the hinge.

Further objects and advantages will appear as the following description is read in connection with the accompanying drawing which forms a part of this application, and in which:

Figure 1 is a perspective view showing a detail of a window frame with a screen hinged in the outer rabbet.

Fig. 2 is a horizontal section taken on the line 2-2 of Fig. 1, and

Fig. 3 is a perspective view of the hinge removed.

Fig. 4 is a detail sectional view showing the position of the hinge on a screen frame.

Referring more particularly to the drawings 1 represents the body of the hinge which is constructed of any suitable type of material and is provided at its side marginal edges with parallel flanges 2 and at its upper end with an attaching lip 3 lying in a plane with the body and provided with a hole 4 to receive a pivot screw or other similar fastening device which is adapted to

be driven into the window frame 6. The body of the hinge is provided with separate

openings 7, either arranged in line or staggered as is desired to receive fastening devices 8 of any suitable character.

It will be understood that the manner in which I have shown the hinge is only one of many conditions under which the hinge may be employed.

In using the present type of hinge to connect the screen frame to the window frame one hinge member is mounted upon each upper end of the frame with the flanges 2 straddling the same and fitting on the inner and outer sides thereof, as shown in Fig. 2 with the lip 3 extending above the screen frame so as to conveniently receive the fastening device. The hinge is then attached by driving in the fastening members 8 which pass through the apertures and enter the wood of the frame as shown. The screen frame is then fitted within the rabbet and the pivot screws or nails are driven into the wood of the window frame. The screen thus normally hangs in a vertical position with its inner face abutting the sash bead 9 and its lower edge contacting with the sill 10. In practice, suitable catches are employed to hold the lower end of the screen from moving outwardly accidentally and as employed the screen frames are provided with a bridging strip 11 which is attached to the upper end of the screen on the inner side and extends between the same and the outer and upper sash as shown to prevent the ingress of flies or other insects.

It is, of course, understood that this strip may be omitted and the screen hinged to the inner surfaces of the opposite sash beads 9. In such instance a suitable stop would be provided for the lower end of the screen to contact with to limit its inward movement. When the lower end of the screen is pushed outwardly the upper end will leave the upper sash and again come in contact with it when the lower end of the screen is pulled inwardly.

Having thus described the invention, what I claim is:

A hinge for screen frames comprising a flat body having longitudinally disposed apertures arranged to receive attaching devices, attaching devices extending there-

- through and entering the wood of the frame, lateral imperforate flanges extending from the side edges of the body and arranged to straddle the vertical pieces of the frame to
5 which the body is attached and lie parallel to each other and to the fastening devices to prevent splitting of the frame and a

longitudinally extending lip formed integrally with the body and having a central aperture to receive a pivot member for the 10 hinge.

In testimony whereof I affix my signature.

JOSEPH B. BRADLEY.
